UNITED STATES PATENT OFFICE.

WILLIAM N. WHITELY, OF SPRINGFIELD, OHIO.

GRAIN-BINDING HARVESTER.

SPECIFICATION forming part of Letters Patent No. 687,547, dated November 26, 1901.

Application filed December 27, 1900. Serial No. 41,295. (No model.)

To all whom it may concern:

Be it known that I, WILLIAM N. WHITELY, a citizen of the United States, residing at No. 153 East High street, Springfield, in the county of Clark and State of Ohio, have invented certain new and useful Improvements in Grain-Binding Harvesters; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in grain-binding harvesters, and principally to a butt-adjusting mechanism. By my new system the grain is moved from the throat of the elevator positively and forcibly over the binder-deck to the grain-binding mechanism.

The subject of this invention broadly is shown and described in my application filed October 29, 1900, Serial No. 34,682.

My improvements, as herein shown and described, particular reference being had to the drawings and specification, consist in a peculiar mechanism for operating and adjusting the butt-adjuster reciprocating toothed-arm member and coacting members thereto to the different lengths of grain to be cut and means to place the grain properly to the binding mechanism that the band may encircle the grain at any desired point in the line of its length.

In grain-harvesters of the type here shown, where a horizontal grain-conveying belt and two elevator-belts are employed, the butts of the cut grain are retarded in their horizontal movement by the standing grain. In consequence the heads travel faster than the butts and the grain is deposited by the elevator upon the binder-deck in an oblique position, the butts hanging back, and the machine is often clogged at the front end of the elevator and front end of the binder-deck. Short, grassy, or wet grain also seriously interferes with the proper working of the machine. The butt-adjuster devices heretofore used to bring the butts of the grain down to the binding mechanism and shape the grain properly

for binding were inadequate and did not relieve the machine of these difficulties, and were constructed to operate only against the butt ends of the grain in a loose fluffy condition, and did not positively control the grain nor clear the elevator and the binder-deck of clogging matter.

The object of my present invention is to overcome these defects and to simplify the construction of my improvements upon butt-adjuster mechanisms shown and described in my application, filed October 29, 1900, Serial No. 34,682.

My improved butt-adjuster mechanism is composed of three principal members, one of said members, an arm having teeth upon its under side lengthwise and crosswise disposed and having a vertically-reciprocating orbital movement, acting upon the grain from the top near the butts, but to some extent influencing the whole mass by the teeth of said arm penetrating the grain from the top downward toward the binder-deck, said arm compressing the grain upon the binder-deck and positively and forcibly moving it over the binder-deck binderward while under compression, moving the butts faster than the heads, clearing the grain and clogging matter off the upper forward ends of the grain-elevator belts, stripping-roller, and binder-deck. Said arm has a horizontal adjustment over the binder-deck while the machine is in operation for the purpose of directing grain of various lengths that it may be bound centrally of its length. This adjustment is effected by constructing the arm in two parts. Each part may have teeth, one part of said arm being an axial pivotal connection between said arm and its driving-crank, the pivotal bearing for the crank-shaft located in the grainward portion of said arm being horizontal, the axis of said pivotal connection between the two parts of said toothed arm being perpendicular to the plane of the binder-deck to allow said arm to swing over the binder-deck parallel to the plane thereof. The object of this peculiar construction and connection of said arm to its driving-crank is that the crank may always rotate in one path, while the opposite end of said arm, having teeth, may be adjusted parallel to the plane of the binder-deck during the working operation of the machine.

and the grain delivered where desired to the band position of the binder. The second member of my improved butt-adjuster consists of a wing-board pivotally connected to the elevator-framework of the machine and extending from the elevator to the binder over the binder-deck, against which the butts of the grain glide binderward from the elevator. Another member of my improved butt-adjuster consists of a pivotally-supported grain-depressor pivotally connected with the binder-deck-cover portion of the elevator part of the machine and extending over the grain upon the binder-deck to the binder mechanism and under which the grain is forcibly drawn by the orbital vertically-reciprocating moving toothed-arm member to the binder mechanism. An adjunct to said butt-adjuster consists of an adjusting-lever pivotally connected to the wing-board member and grain-depressor member and extending over the binder-deck-cover portion of the elevator within reach of the operator. The butt-adjuster mechanism is entirely independent of the binder mechanism in its adjustments, movements, and operations, each being separately and independently adjusted. I attain these objects by means of the mechanism shown in the accompanying drawings, in which—

Figure 1 is a front elevation of a grain-binding harvesting-machine, showing the reciprocating toothed-arm member of the butt-adjuster driven by a sprocket-chain from the forward end of the upper elevator-roller. Fig. 2 is a front elevation of a portion of a grain-binding harvesting-machine, showing the reciprocating toothed-arm member of the butt-adjuster driven by a pair of intermeshing gears and deriving its motion from one of the three elevator-rollers, the third or stripping roller in this case. Fig. 3 is a plan view showing one construction of the butt-adjuster mechanism comprising the toothed-arm member, the wing-board member, grain-depressor member, and accessories thereto. In this form of construction the toothed-arm member is not adjustable parallel to the plane of the binder-deck, but operates in one path only. Fig. 4 is a plan view showing another construction of the butt-adjuster mechanism, the toothed arm made in one piece, having an axial vertical pivotal connection at its front end to its driving-crank and a universal pivotal connection at its rear end, that the toothed-arm member, wing-board member, and grain-depressor member may swing horizontally over the grain-binder deck for adjustment of the grain endwise and sidewise. Fig. 5 is a detail rear elevation showing the driving-gears for the third or stripping roller. Fig. 6 is an elevation of the toothed-arm butt-adjuster member, showing its axial vertical pivotal connection to its driving-crank at its front end and a universal pivotal connection to its vibrating swinging link at its rear end. Fig. 7 is a plan view of same, the dotted lines

showing the toothed arm horizontally adjusted on its axial vertical pivot. Fig. 8 is a plan view of the toothed-arm member, wing-board member, and grain-depressor member of the butt-adjuster, showing the toothed-arm member in various positions of its movements, the toothed-arm member being made solid and axially vertically pivotally connected at its front end to its driving-crank shaft and universally pivotally connected at its rear end to a vibrating swinging link to admit of horizontal adjustment over the binder-deck. Fig. 9 is an elevation showing another construction of the toothed arm, in which the arm is divided, each portion having teeth. The forward portion is provided with a horizontal crank-bearing for its driving-crank and is axially vertically pivotally connected to the other portion of said arm to admit of horizontal adjustment. The rearward portion of said arm is universally pivotally connected to its vibrating swinging link connection to the wing-board member. Fig. 10 is a plan view of same. Fig. 11 is a perspective view of same, showing parts composing said toothed arm detached. Fig. 12 is a detail sectional cross view at the points y of the toothed arm. (See Fig. 9.) Fig. 13 is a detail top view, partly in section, of the sprocket-chain wheels for driving the toothed-arm member, also showing the driving-crank of the toothed-arm member, its journal, and stationary box. Fig. 14 is a detail side view showing the chain sprocket-wheels and chain for driving the toothed-arm member. Fig. 15 is a detail side and front view of the vibrating swinging link that connects the rearward end of the toothed-arm member to the wing-board member. Fig. 16 is a detail front and side view of the universal pivotal box connection of the rearward end of the toothed-arm member to the vibrating swinging link. Fig. 17 is a detail side view of the vertically-rotating driving-crank and journal which connects the forward end of the toothed-arm member to the single-piece metallic box on front of the elevator-framework. Fig. 18 is a detail front view of the forward portion of the toothed-arm member, showing the teeth crosswise disposed.

Similar letters of reference indicate like parts in the several views.

Fig. 1 shows a grain-binding harvesting-machine having the usual cutting apparatus A, divider A', horizontal grain-conveying belt A², inclined elevator A³, binder-deck intermediate A⁴, and binder mechanism A⁵. To the upper forward end of the elevator is secured a single-piece metallic box A⁶, which forms a support for the journal-bearing for the elevator-roller shafts A⁷ and A⁸ and the stripping-roller shaft A⁹ and supports for the intermediate gear-wheels A¹⁰ and A²⁰. Through the medium of the intermediate gears A¹⁰ A²⁰ motion is communicated from the gear-wheel A¹², located on the forward end of the elevator-roller shaft A⁸, to the gear-wheel

A^{21} , located on the forward end of the top-elevator-roller shaft A^7 to cause the top roller A^{18} of the upper elevator to revolve in the proper direction and also the gear-wheel A^{22} , located on the forward end of the stripping-roller shaft A^9 , to revolve the stripping-roller A^{15} in the right direction with the flow of the grain from the elevator. To the rearward end of the roller-shaft A^8 is secured the sprocket-wheel A^{10} , Fig. 4, which derives its motion by means of a chain belt from the main drive of the machine in the usual manner. Upon the rearward end of the upper roller-shaft A^8 of the lower elevator is secured the gear-wheel A^{14} , which through the medium of the intermediate gear-wheel A^{23} communicates motion to the gear-wheel A^{24} , located on the rearward end of the stripping-roller shaft A^9 , Fig. 5, and rotates the stripping-roller A^{15} in the right direction and with the flow of the grain from the elevator. Upon the forward end of the roller-shaft A^7 is secured a sprocket-wheel A^{16} , which transmits motion through the medium of a chain belt A^{17} to the reciprocating toothed-arm-driving sprocket-wheel A^{18} . The single-piece metallic box A^6 is further provided with a rigid journal-box B for the reciprocating toothed-arm crank-shaft B' , its outer end being secured to the driving sprocket-wheel A^{18} , which receives its motion from the upper roller-shaft of the upper elevator by means of the chain belt A^{17} , as shown in Fig. 1.

In Fig. 2 is shown a modified form of driving mechanism for operating the reciprocating toothed-arm member. In this construction the stripping-roller shaft A^9 is provided at its front end with a gear-wheel B^2 , which engages the gear-wheel B^3 , located upon the reciprocating toothed-arm crank-shaft B' . It will be observed that the driving mechanism for the crank which operates the reciprocating toothed-arm member of the butt-adjuster is stationary so far as any adjustments are concerned.

Either of the above methods of driving the crank which operates the reciprocating toothed-arm member I have found practical; but as they are fixed in their positions it is necessary to provide means for horizontal adjustment of the butt-adjuster and at the same time reciprocate the toothed-arm member to deliver the grain to the band of the binder at any point desired in the line of its length. With this end in view it will be noticed that the wing-board C is pivotally connected perpendicular to the plane of the binder-deck to the single-piece metallic box A^6 by the hinge $C' C'$, a portion of which is formed on the box A^6 and a corresponding portion on said wing-board, the two portions pivotally connected by means of the pin C^2 . To the outer side of the wing-board member C is rigidly secured a pivotal socket C^3 to receive the lower end of the horizontal adjusting-rod C^4 , which extends upward and over the reciprocating toothed-arm member and

over the binder-deck-cover portion of the elevator to a point within reach of the operator, said adjusting-rod provided with notches C^5 to engage the stop C^6 , secured to the top of the binder-deck-cover portion of the elevator and be held in any position of adjustment.

The reciprocating toothed-arm member D is pivotally connected to the vertically-rotary crank D' and driven by said rotary crank D' . The shaft of the crank D' is supported by and rotated in a stationary non-adjustable bearing B , (shown in Figs. 3 and 4,) formed in the single-piece metallic box A^6 ; and for the purpose of adjustment it becomes necessary to pivotally connect the grainward end of said reciprocating toothed-arm member D to the journal-box D^2 , the pivotal axis of which is vertical to the plane of the binder-deck, said journal-box having a horizontal bearing for the driving-crank shaft, (shown in Figs. 4, 6, and 7,) and the stubbleward end of said reciprocating toothed-arm member is universally pivotally connected to the upper end of the vibrating swinging link D^8 by a universally pivotal box D^8 . The lower end of said link is pivotally connected to the wing-board member C , permitting the proper horizontal adjustment of said wing-board for long or short grain.

I prefer to construct the reciprocating toothed-arm member as shown in Figs. 9 and 10, the arm being divided. The grainward portion of the toothed-arm member D is a detached toothed head D^4 , which has formed upon it the horizontal driving-crank bearing D^6 and the axial vertically-pivotal connection D^6 . Said toothed-head portion D^4 is not pivotally adjustable parallel to the plane of the binder-deck. The middle portion of the toothed arm is axially pivotally connected perpendicular to the plane of the binder-deck to the forward portion D^4 by the vertical pivot D^6 to admit of adjustment over the binder-deck parallel to the plane thereof. The forward end of the arm D is adapted to receive the vertical pivot D^6 , formed on the grainward portion D^4 , and is held in place by a bolt D^7 , thereby completing the horizontal and vertical pivotal connection of the forward end D^4 of the toothed-arm member to the driving-crank D' .

The stubbleward part of the reciprocating toothed arm D is provided with a universal pivotal connection E , made to fit over and on the pin E' of the vibrating swinging link D^8 , and also provided with lugs $E^2 E^2$ to fit over the end of said arm and is held in place by the bolt E^3 , passing through the lugs $E^2 E^2$ and the stubbleward end of the toothed arm D , thus completing the pivotal connection of the rearward end of said arm to the vibrating swinging link, the lower end of said link pivotally connected to the wing-board C .

By referring to Fig. 8 it will be observed that in the adjustment of the wing-board and reciprocating toothed arm a curvilinear move-

ment is produced in which the grain is brought downward and rearward toward the binder mechanism. The driving-crank D' being supported in a rigid journal-box B, formed in the single-piece metallic box A⁶, its movement is in a straight line. The grainward end of the reciprocating toothed-arm member is pivotally connected to the driving-crank D', the axial line of said pivot 10 being perpendicular to the plane of the binder-deck, its stubbleward end universally pivotally connected to the upper end of the vibrating swinging link D⁸ by the universal pivotal box D⁹, the lower end of said link 15 pivotally connected to and supported by the wing-board member. The reciprocating toothed-arm member has two movements—the grainward end practically in a straight line back and forth, while its stubbleward end 20 moves obliquely thereto, and between these points a curved movement takes place.

To the binder-deck-cover portion F of the elevator is secured the eyepiece F', which pivotally supports the grain-depressor member F², the upper portion of said grain-depressor extending downward, passing through the clip F³, secured to the operator's adjusting-rod C⁴. The lower portion of said grain-depressor member F² extends downward over 25 the binder-deck to near the binder mechanism, said grain-depressor member F² being pivotally connected to the binder-deck-cover portion of the elevator F and flexibly connected to the adjusting-rod C⁴, which is pivotally connected to the wing-board member C. It will be observed that the reciprocating toothed-arm member D, the wing-board member C, and grain-depressor member F² are adjusted to the desired position at one 30 and the same time. The function of the grain-depressor member F² is to hold the grain down as it is drawn under it by the reciprocating toothed-arm member D and confine it to the binder-deck while being conveyed to 35 the binder mechanism by said arm member D.

Referring to Fig. 1, a link-belt driving mechanism for the toothed arm is shown with an idler D⁹ for the purpose of tightening the link belt A¹⁷ or loosening the same for removal.

In Fig. 13 is shown an eccentric-box G, adapted to fit into the rigid journal-bearing box B to receive and support the crank-shaft B', to one end of which is secured the sprocket-wheel A¹⁸ by the pin G'. Said box G has a projecting arm or lug G', provided to move the eccentric-box from one point to another and held in position by a pin G³.

What I claim, and desire to secure by Letters Patent of the United States, is—

1. In a grain-binding harvester, in combination, a horizontal grain-conveying belt, a pair of grain-elevator belts, a binding mechanism, a binder-deck between the elevator and the binding mechanism, a grain-butt-adjuster mechanism located between the grain-elevator and grain-binder mechanism, and sup-

ported by the elevator portion of the machine; and adjustable parallel to the plane of the binder-deck, composed principally of three 70 coacting members each pivotally supported: first, a wing-board member pivotally connected to the elevator part of the machine, to swing parallel to the plane of the binder-deck and control the butts of the grain in 75 their descent to the binder mechanism; second, a grain-depressor member pivotally connected to a fixed part of the machine and located over and above the path of the grain upon the binder-deck, and under which the 80 grain is forced; third, a vertically-reciprocating orbitally-moving arm member having downwardly-projecting teeth located over the forward end of the binder-deck between said wing-board member and grain-depressor 85 member, moving grainward above the path of the butts of the grain near the butts in one portion of its orbit and into and with the grain near the butts in its return motion, a vibrating swinging link member, its upper 90 end universally pivotally connected to the stubbleward end of said toothed-arm member, the lower end of said link pivotally connected to said wing-board member at its stubbleward end, the grainward end portion of 95 said toothed-arm member being pivotally connected to the main portion of said toothed-arm member, the axis of said pivotal connection being perpendicular to the plane of the binder-deck to admit of adjustment of said 100 toothed-arm member over the binder-deck parallel to the plane thereof; a vertically-rotary driving-crank, its shaft horizontally disposed, said crank located over the path of the butts of the grain and pivotally connected 105 to the grainward end of said toothed-arm member by a suitable bearing located thereon; a single-piece metallic box secured to the forward upper portion of the elevator-framing forming a support for the forward ends 110 of the upper roller-shafts of the upper and lower elevators, the driving mechanism for the toothed-arm member, the stripping-roller shaft, the horizontal journal-bearing for the 115 rotary driving-crank shaft for the toothed-arm member of the butt-adjuster and a pivotal support for the wing-board member of the 120 butt-adjuster; said reciprocating toothed-arm member adjustable parallel to the plane of the binder-deck by means of its pivotal connection with the bearing for the crank-shaft to adjust grain of different lengths suitably to the binder mechanism for binding the gavels centrally.

2. In a grain-binding harvester, in combination, a horizontal grain-conveying belt, a pair of grain-elevator belts, a binder mechanism, a binder-deck between the elevator and the binding mechanism, a grain-butt-adjuster mechanism supported by the elevator portion of the machine independent of the binding mechanism, one of its members consisting of a vertically-reciprocating orbitally-moving arm having downwardly-projecting

- teeth located above the forward end of the binder-deck and moving into the path of the grain near the butts thereof, to compress the grain down upon the binder-deck, a vertically-revolving driving-crank located above the path of the butts of the grain, its shaft horizontally disposed, the pin of said crank extending rearward over the path of the butts of the grain and pivotally connected to the grainward end of said toothed-arm member by a suitable bearing thereon, the shaft of said crank rotated by a connecting driving mechanism with one of the grain-moving rollers, the bearing of said crank-shaft being stationary upon the elevator-frame, the toothed-arm member having a vertically-reciprocating movement and simultaneous movement parallel to the plane of the binder-deck, the grainward end of said toothed arm pivotally connected to its driving-crank bearing for adjustment over the binder-deck parallel to the plane thereof, a vibrating swinging link universally pivotally connected at its upper end to the stubbleward end of said toothed-arm member, a wing-board member extending over the binder-deck from the elevator to the binding mechanism along the butts of the grain, the grainward end of said wing-board member pivotally connected to the elevator portion of the machine, its stubbleward end forming a support for the vibrating swinging link and free to be adjusted over the binder-deck parallel to the plane thereof for the purpose set forth and described.
3. In a grain-binding harvester, in combination, a horizontal grain-conveying belt, a pair of grain-elevator belts, a grain-binder mechanism, a binder-deck between the elevator and binder mechanism, a butt-adjuster mechanism, one member thereof consisting of an orbitally-moving, vertically-reciprocating arm member, having downwardly-projecting teeth, and located over the forward end of the binder-deck, means for moving said member alternately stubbleward and grainward above the path of the butts of the grain in one portion of its orbit and moving into and with grain in its return motion to move the grain binderward; said toothed-arm member extending grainward above a considerable portion of the grain upon said binder-deck near the butts thereof, and compressing it upon said binder-deck; a driving-crank for said toothed arm having a horizontal shaft journaled in a stationary bearing in the elevator-framework, said toothed arm pivotally connected to its driving-crank bearing, the axis of said pivotal connection being perpendicular to the plane of the binder-deck for the purpose of adjustment parallel to the plane of the binder-deck during its vertically-reciprocating movements, a wing-board member at the butts of the grain, pivotally connected to the elevator-frame and extending from near the grain delivery end of the elevator toward the binding mechanism and against which the butts of the grain glide in passing toward the binding mechanism; a grain-depressor member pivotally connected to a fixed portion of the machine, under which the grain is forced by the action of the reciprocating toothed-arm member; said wing-board member, grain-depressor member and reciprocating toothed-arm member each having an independent pivotal connection to the elevator portion of the machine to admit of adjustment parallel to the plane of the binder-deck for the purpose set forth and described.
4. In a grain-binding harvester, in combination, a horizontal grain-conveying belt, a pair of grain-elevator belts, a grain-binding mechanism, a grain-binder deck between the elevator and binding mechanism, a grain-butt-adjuster mechanism, connected with and supported by the elevator-framework of the machine, one member thereof consisting of a vertically-reciprocating, orbitally-moving arm, having downwardly-projecting teeth, and located above the path of the butts of the grain and moving into the grain to move it binderward; a vibrating swinging link universally pivotally connected at its upper end to the stubbleward end of said toothed-arm member, the wing-board member of said butt-adjuster to which the lower end of the swinging link is pivotally connected, the grainward end of said toothed-arm member pivotally connected to the main portion of the toothed-arm member, the axis of said pivotal connection being perpendicular to the plane of the binder-deck to move in adjustment over the binder-deck parallel to the plane thereof for the purpose of adjusting the two portions of said toothed-arm member, a crank having a bearing on the grainward end portion of the toothed-arm member, the shaft of said crank having a horizontal bearing, said crank-shaft, horizontal bearing and crank remaining in their normal positions unaffected by the swinging adjustment of the main body of said toothed-arm member as set forth and described.
5. In a grain-binding harvester, in combination, a horizontal grain-conveying belt, a pair of grain-elevator belts, a binder mechanism, a binder-deck between the elevator and grain-binding mechanism, a butt-adjuster mechanism, one of its members composed of two parts, both parts provided with downwardly-projecting teeth on their under sides and located over the forward end of the binder-deck, said member to act downward upon the grain and into the grain near the butts to move the grain toward the binder mechanism from the elevator, a vertically-rotary crank, the shaft of said crank horizontally disposed, said crank located above the path of the butts of the grain, and pivotally connected to the grainward end of said toothed-arm member by a crank journal-bearing located thereon, a single-piece metallic box secured to the forward upper portion of the elevator-framing having a horizontal stationary bearing for the forward end of said crank-shaft, a pivotal joint connection between the grainward end

- of said toothed-arm member and the stubbleward-extending portion of said toothed-arm member, the axis of said pivot being perpendicular to the plane of the binder-deck and 5 on which the said toothed-arm member can turn for adjustment parallel to the plane of the binder-deck while being reciprocated vertically by the rotary crank for the purpose of turning the stalks of the grain on the binder-deck from an oblique position to a parallel 10 one with the forward motion of the machine to form the gavels properly for binding.
6. In a grain-binding harvester, in combination, a horizontal grain-conveying belt, a 15 pair of grain-elevator belts, a binding mechanism, a binder-deck between the elevator and grain-binder mechanism, a butt-adjuster mechanism, one member thereof consisting of a reciprocating orbitally-moving toothed 20 arm, composed of two parts, each part having downwardly-projecting teeth and located over the forward end of the binder-deck, means for moving said member alternately stubbleward and grainward, said member acting 25 grainward above the path of the grain in one portion of its orbit and downward and into the path of the grain in its return motion to compress the grain and hold it onto the binder-deck and move it binderward under compres- 30 sion; a rotary crank having a horizontal shaft, said crank being located over the path of the butts of the grain, the grainward portion of said toothed arm being pivotally connected thereto, the two portions of the arm being 35 connected by a pivot, the axis of said pivot being perpendicular to the plane of the binder-deck, the main portion of said arm being thus connected to the crank by a universally-pivoted swinging joint for the purpose of adjust- 40 ment parallel to the plane of the binder-deck to move the grain from the elevator to the binder mechanism and adjust it lengthwise central to the band be it long or short.
7. In a grain-binding harvester, in combination, a horizontal grain-conveying belt, a 45 pair of grain-elevator belts, a grain-binder mechanism, a binder-deck between the elevator and binder mechanism, a butt-adjuster mechanism, one of its members consisting of 50 a vertically-reciprocating orbitally-moving arm having downwardly-projecting teeth on its under side and located over the forward end of the binder-deck, acting above the grain in one portion of its orbit and in the path of 55 the grain and with the grain in another portion of its orbit to compress it onto the binder-deck to forcibly move it to the binder mechanism; a vertically-moving rotary crank having a horizontal bearing in said toothed arm, 60 the shaft of said crank horizontally journaled in a stationary bearing in the elevator-frame and driven from one of the grain-moving roller-shafts, a pivotal connection between said crank and the main portion of said 65 toothed arm at its grainward end, the axis of said pivot being perpendicular to the plane of the binder-deck to admit of adjustment of

the stubbleward end of said toothed-arm member parallel to the plane of the binder-deck when in reciprocating motion for the 70 purposes set forth and described.

8. In a grain-binding harvester, in combination, a horizontal grain-conveying belt, a pair of grain-elevator belts, a grain-binder mechanism, a binder-deck between the elevator and binding mechanism, a grain-butt-adjuster mechanism located between the grain-elevator portion of the machine and grain-binder mechanism and supported by the elevator portion of the machine, one member 80 thereof consisting of a vertically-reciprocating orbitally-moving arm, having downwardly-projecting teeth on its under side, and located over the forward end of the binder-deck, said member operating above and moving into the path of the grain near the butts thereof, a driving-crank for said toothed arm, the grainward end of said arm pivotally connected to its driving-crank bearing for adjustment over the binder-deck parallel to the 85 plane thereof, a vibrating swinging link to which the stubbleward end of said arm is pivotally connected by a universal joint, a wing-board member of the butt-adjuster pivotally connected at its grainward end to the 90 elevator-frame construction, the axis of said pivot being perpendicular to the plane of the binder-deck and adapted for adjustment of said wing-board member at its stubbleward 95 end, over the binder-deck parallel to the plane thereof to adjust grain of different lengths central to the band for binding, the lower end of said link being pivotally connected to the stubbleward portion of said wing-board member. 100

9. In a grain-binding harvester, in combination, a horizontal grain-conveying belt, a pair of grain-elevator belts, a grain-binder mechanism, a binder-deck between the elevator and binder mechanism, an upper roller-shaft for the upper grain-elevator belt, an upper roller-shaft for the lower grain-elevator belt, a grain-stripping roller located between the upper end of said lower grain-elevator belt and binder-deck, a grain-butt-adjuster mechanism located between the grain-elevator and grain-binder mechanism and supported by the elevator portion of the machine, one member thereof consisting of a vertically-reciprocating orbitally-moving arm having downwardly-projecting teeth located over the forward end of the binder-deck, a vertically-rotary crank for driving said arm and located over the path of the butts of the grain and pivotally connected to the grainward end portion 115 of said arm, a driving-shaft for said crank horizontally disposed, a single-piece metallic box located on the forward upper end of the elevator portion of the machine having a horizontal stationary bearing for the forward 120 end of said crank-shaft, forming a support for the forward ends of all of said roller-shafts, a driving-gear mechanism for said toothed arm located in front of said single-piece metallic 125 130

box and connected with one of said roller-shafts.

10. In a grain-binding harvester, in combination, a horizontal grain-conveying belt, a pair of grain-elevator belts, a grain-binder mechanism, a binder-deck between the elevator and binder mechanism, a butt-adjuster mechanism, one member thereof consisting of a vertically-reciprocating orbitally-moving 50 arm having downwardly-projecting teeth located over the forward end of the binder-deck, said arm moving grainward above the path of the butts of the grain in one portion of its orbit and into and with the grain near the butts thereof in another portion of its orbit to move the grain binderward over the binder-deck toward the binding mechanism, a vertically-rotary crank for driving said arm, the shaft of said crank horizontally disposed; 55 said crank located over the path of the butts of the grain and pivotally connected to the grainward end portion of said arm by a suitable bearing thereon, a driving-gear mechanism directly from the forward end of the upper roller-shaft of the upper elevator to said crank-shaft, said roller-shaft and said crank-shaft revolving in the same direction to change the flow of the grain from an upward to a downward direction binderward.
- 30 11. In a grain-binding harvester, in combination, a horizontal grain-conveying belt, a pair of grain-elevator belts, a grain-binder mechanism, a binder-deck between the elevator and grain-binder mechanism, grain-moving and butt-adjuster mechanism, one member thereof consisting of a reciprocating orbitally-moving arm having downwardly-projecting teeth and located over the forward end of the binder-deck and driven directly from the forward end of the upper roller-shaft of the upper elevator-belt, a driving-crank for the toothed arm, a chain-gearing connecting said roller-shaft and driving-crank shaft, by means of toothed sprocket-wheels located on the forward ends of said shafts, each rotating in the same direction, the toothed sprocket-wheel on said roller-

shaft being smaller than the toothed sprocket-wheel located on said driving-crank shaft causing the toothed-arm member to move at 50 a slower speed than said upper roller-shaft, the shaft of said crank horizontally disposed and a single-piece metallic box secured to the forward upper portion of the elevator having a stationary bearing in which said crank-shaft is journaled; said parts disconnected from and independent of the binder mechanism and its adjustments.

12. In a grain-binding harvester, in combination, a horizontal grain-conveying belt, a pair of grain-elevator belts, a grain-binder mechanism, a binder-deck between said grain-elevator and grain-binder mechanism, a grain-butt-adjuster mechanism, one member thereof consisting of a vertically-reciprocating orbitally-moving arm, having downwardly-projecting teeth, and located over the forward end of the binder-deck and driven directly from the forward end of the upper roller-shaft of the upper elevator, a rotary driving-crank, a single-piece metallic box secured to the forward upper end of the elevator and having a bearing, the shaft of said crank horizontally disposed and journaled in said bearing, the rearward end of said shaft extending over the path of the butts of the grain and its crank pivotally connected to the grainward end of said toothed-arm member, a chain-and-sprocket connection between the forward ends of said crank-shaft and upper 80 shaft of the upper elevator, the toothed sprocket-wheel located on the upper roller-shaft of the upper elevator being smaller than the toothed sprocket-wheel located on said driving-crank shaft to impart a slower motion to said toothed-arm member than said roller-shaft; all of said parts independent of the binder mechanism and its adjustments.

In testimony whereof I affix my signature in presence of two witnesses.

WILLIAM N. WHITELY.

Witnesses:

JOHN L. GILLIGAN,
FRED STATE.
